UNITED STATES PATENT OFFICE

154,743

DESIGN FOR A TAXICAB

Lynn Brodton, New York, N. Y.

Application September 4, 1947, Serial No. 141,208

Term of patent 14 years

(Cl. D14—3)

To all whom it may concern:

Be it known that I, Lynn Brodton, a citizen of the United States, residing at city of New York, county of New York, and State of New York, have invented a new, original, and ornamental Design for Taxicab, of which the following is a specification, reference being had to the accompanying drawing, forming a part thereof, wherein:

Fig. 1 is a perspective view looking from the front toward the rear of the taxicab of my new design; and

Fig. 2 is a perspective view looking from the rear toward the front of a taxicab.

The characteristic features of my design reside

in the portions shown by means of full lines in the drawing.

I claim:

The ornamental design for a taxicab, substantially as shown and described.

LYNN BRODTON.
